US0D1112155S

(12) **United States Design Patent** (10) **Patent No.:** **US D1,112,155 S**
Worth et al. (45) **Date of Patent:** ** *Feb. 10, 2026

(54) **HEADSET WITH DETACHABLE HEADBAND**(71) Applicant: **Cognito Therapeutics, Inc.**,
Cambridge, MA (US)(72) Inventors: **Cory Worth**, San Diego, CA (US);
Yousef Awwad, Merrimack, NH (US);
Kim Kwan, Mashpee, MA (US); **Divya Cohen**, San Francisco, CA (US); **Brent Vaughan**, Cambridge, MA (US); **Dina Dajani**, San Francisco, CA (US); **Matt Wagers**, Cambridge, MA (US); **Annie Zhang**, Plano, TX (US)(73) Assignee: **Cognito Therapeutics, Inc.**,
Cambridge, MA (US)

(*) Notice: This patent is subject to a terminal disclaimer.

(**) Term: **15 Years**(21) Appl. No.: **29/907,459**(22) Filed: **Jan. 5, 2024**(51) **LOC (15) Cl.** ..... **14-01**(52) **U.S. Cl.**USPC ..... **D14/205**; D14/372; D24/187(58) **Field of Classification Search**

Primary Examiner — Paula Allen Greene(74) *Attorney, Agent, or Firm* — Wilson Sonsini Goodrich & Rosati(57) **CLAIM**

The ornamental design for headset with detachable headband as shown and described.

DESCRIPTION

FIG. 1 is a perspective view of a headset with detachable headband showing the new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a bottom view thereof; and,

FIG. 8 is a disassembled perspective view thereof.
